Inventor A. P. Winslow

United States Patent Office.

A. P. WINSLOW, OF CLEVELAND, OHIO.

Letters Patent No. 74,969, dated February 25, 1868.

IMPROVEMENT IN RAILROAD-CAR STOVES.

The Schedule referred to in these Letters Patent and making part of the same.

TO ALL WHOM IT MAY CONCERN:

Be it known that I, A. P. WINSLOW, of Cleveland, in the county of Cuyahoga, and State of Ohio, have invented certain new and useful Improvements in Railroad-Stoves; and I do hereby declare that the following is a complete description of the same, reference being had to the accompanying drawings making part of this specification, in which—

Figure 1 is a side view of the stove.

Figure 2 is an end view.

Figure 3 is a longitudinal section.

Like letters of reference refer to like parts in the different views presented.

My invention is designed to act as a preventive of those frightful casualties which sometimes occur from the communication of fire to the inflammable material of the car, when colliding, or thrown from the track upon its side, capsized, or placed in any position by which the fire is thrown from the stove, there often being no way of egress for the passengers, and thus many lives are lost before help can be had.

A, fig. 1, represents the stove, which may be of any desirable form or configuration suitable for the object desired. Underneath it is the hollow platform or water-chamber, B. Connected with this platform, and surrounding the stove, as shown in the drawings, are the pipes C. Also inside the stove, and communicating with the platform, are the pipes D, fig. 3. These pipes are perforated, for a purpose hereafter shown. A short distance from the top of the stove is the perforated diaphragm E. Connected to this diaphragm, and also to the top of the stove, are the guards a, which are for the purpose of preventing the fire from passing through the pipe d in case of accident, and also allows a free draught from the fire. F is a perforated shell, surrounding the stove, for the purpose of protecting the garments of passengers from the hot surface while passing. The dotted lines G represent a water-jacket for protecting the sides of the car from injury by the heat of the stove, and is also an auxiliary water-chamber. This is filled with water, but has no communication with the platform before mentioned.

The platform B is filled with water through the opening e, which is then closed by any desirable means. In case the car should be thrown from the track in any position, the water from this platform will be thrown into the pipes C D, and thence through the holes immediately upon the fire, thus extinguishing it and preventing any danger from the same. Also, in case of a collision, when the two cars meet and the stove is crushed, the platform is composed of such material as to be broken, and thus the water will be thrown upon the fire. The water-jacket G also, when crushed, aids in extinguishing the fire. Should the car be in any dangerous position, out of its ordinary course, raised to one side or the other, the water from the pipes D will be ejected on the fire in the stove, thereby extinguishing it; and should it cause cinders and ashes to rise, as the door of the stove may be secured by a key in the ordinary way, they could find no egress there; hence they are caught by the guards a, which retain all the ashes and fire. Thus, as the ashes and cinders escape through the opening h, they are caught on the first guard, which acts as a shelf to retain it, and what escapes from the first is caught by the second, and so on, as it should be thrown from one guard to the other, no fire or cinders can escape through the pipe d, so as to cause danger by ignition. The water from the outside pipes is thrown on the floor and surrounding objects, thus saturating them and rendering ignition difficult.

I do not confine myself to any particular arrangement of the pipes, but they may be placed across the stove, or in any position which may be desired.

What I claim as my improvement, and desire to secure by Letters Patent, is—

1. The water-chamber or tank B, and perforated water-pipe D, in combination with a railroad-stove, substantially as and for the purpose set forth.

2. The guards a, in combination with a stove, substantially as and for the purpose set forth.

A. P. WINSLOW.
